US00D890146S

(12) **United States Design Patent** (10) **Patent No.:** **US D890,146 S**
(45) **Date of Patent:** **** Jul. 14, 2020**

(54) **ANTENNA**

(71) Applicant: **Airgain Incorporated**, San Diego, CA (US)

(72) Inventors: **Mark Montgomery**, Melbourne Beach, FL (US); **Devis Iellici**, Cambridge (GB); **Bei Zheng**, Zhang Jia Gang (CN)

(73) Assignee: **Airgain Incorporated**, San Diego, CA (US)

(**) Term: **15 Years**

(21) Appl. No.: **29/700,753**

(22) Filed: **Aug. 5, 2019**

Related U.S. Application Data

(62) Division of application No. 29/615,962, filed on Aug. 31, 2017, now Pat. No. Des. 857,671.

(51) **LOC (12) Cl.** **14-03**

(52) **U.S. Cl.**

USPC **D14/230**

(57) **CLAIM**

The ornamental design for an antenna, as shown and described.

DESCRIPTION

FIG. 1 is a top plan view of an antenna, showing our new design;

FIG. 2 is a front elevation view thereof;

FIG. 3 is a bottom plan view thereof;

FIG. 4 is a top perspective view thereof;

FIG. 5 is a top plan view thereof, with the broken line environment not shown; and,

FIG. 6 is a front elevation view thereof, with the broken line environment not shown.

The broken lines show environment only and form no part of the claimed design.

1 Claim, 4 Drawing Sheets
